United States Patent Office

Des. 193,943
Patented Oct. 30, 1962

193,943

HAND WINCH

Robert H. Gray, 4420 NE. Maywood Place,
Portland, Oreg.

Filed Oct. 23, 1961, Ser. No. 67,227

Term of patent 14 years

(Cl. D41—1)

FIG. 2

FIG. 3

FIG. 1

FIG. 4

FIG. 5

FIG. 1 is a front perspective view taken from the top and one side of a hand winch embodying my new design;
FIG. 2 is a front elevational view thereof;

FIG. 3 is an elevational view thereof taken from the side opposite that shown in FIG. 1;

FIG. 4 is a rear elevational view thereof; and
FIG. 5 is a bottom plan view thereof.

I claim:
The ornamental design for a hand winch, as shown.
